UNITED STATES PATENT OFFICE.

GUNIL J. HANSON, OF MINNEAPOLIS, MINNESOTA.

COLLAPSIBLE TOY HOUSE.

Application filed April 14, 1921. Serial No. 461,182.

To all whom it may concern:

Be it known that I, GUNIL J. HANSON, a citizen of the United States, residing at Minneapolis, in the county of Hennepin and 5 State of Minnesota, have invented certain new and useful Improvements in Collapsible Toy Houses, of which the following is a specification.

My invention relates to collapsible toy houses. An object is to provide a construction whereby the house may be packed flat and readily assembled whenever desired in such manner that the various parts will be locked together when the house is completely 10 assembled. Another object is to provide a device of this character which will afford amusement for children and at the same time will be instructive.

The full objects and advantages of my invention will appear in connection with the detailed description, and the novel features embodied in my inventive idea will be particularly pointed out in the claims.

In the accompanying drawings which 25 illustrate an embodiment of my invention, Fig. 1 is a side elevational view of my toy house assembled. Fig. 2 is a front elevational view thereof. Fig. 3 is a view in vertical section on the line 3—3 of Fig. 1. Fig. 4 is a view in vertical section on the line 4—4 of Fig. 2. Fig. 5 is a fragmentary view of the rear of the house. Fig. 6 is a view in vertical section on the line 6—6 of Fig. 5. Fig. 7 is a view in vertical section on the line 7—7 35 of Fig. 4. Fig. 8 is a top plan view of a ceiling member. Fig. 9 is a view in horizontal section on the line 9—9 of Fig. 3. Fig. 10 is a vertical section on the line 10—10 of Fig. 2.

Referring to the construction shown in the 40 drawings, the numeral 12 designates a rear wall member which has a dovetailed strip 14 secured to its lower outside surface. A chimney piece 16 is provided with a dovetailed recess 18 with which the strip 14 fits as shown 45 in Figs. 6 and 9, so that the chimney piece may be slid into place. The wall member 12 is provided with window frames 20, the construction of which will be described later. Secured to the inner surface of the wall member 12 is an upper grooved horizontal strip 22, a lower horizontal plain strip 24, and vertical grooved strips 26. Two side wall members 28 are provided, and each of these members has secured to its inner surface an upper 50 grooved horizontal strip 30, a lower horizontal plain strip 32, and vertical grooved strips

34, 36, and 37, the strips 37 being attached at the front of a lower forwardly extending portion of the side member. In assembling the device, the ends of the rear wall member are fitted into grooves of strips 34 carried by the side wall members and the inclined surfaces of blocks 38 engage inclined surfaces of blocks 40 carried by the side members so that the side members are held to the 60 rear wall member. A front base member 42 fits at its ends into grooves of the strips 37 and is provided with blocks 44 having inclined edges which engage the inclined edges of blocks 46 for locking the parts together. 65 When the base member 42 is in place, a floor member 48 is slid into position so as to rest upon the horizontal strips 24 and 32 and upon the top of the base member. Secured to the upper surface of the floor member are a pair 70 of grooved strips 50 which extend from the rear of this member part way to the front thereof, and also secured to the floor member are pairs of grooved strips 52 and 54 which extend in a direction at right angles to the 75 strips 50 but are located toward the front corners of the floor member. A ceiling member 56 is then slid into place, the rear edge of this member fitting into the grooves of the strips 22 and the ends of this member fitting 80 into the grooves of the strips 30. The front of the ceiling member carries a vertical member 58 and short grooved strips 60 which fit the lower edges of overhanging portions of the side wall members as will be apparent 85 from Fig. 1. A roof member is provided 90 which consists of front and rear leaves 62 and 64 hinged together at their adjacent edges which are provided with strips 66 and 68 to which is glued or otherwise secured a 95 piece of flexible material 70 which permits the two leaves to be folded together when the device is to be packed. The rear leaf has a notch 72 for the passage of the chimney member 16 and both leaves are provided with 100 grooved strips 74 which receive the upper inclined ends of the side wall members. Hooks 76, carried by the ceiling member, are adapted to be hooked into eyes 78 carried by the leaf 64 whereby the roof member is held 105 in place. Partition members 80 having door openings 81 as shown in Fig. 4 are adapted to slide in the grooves of the strips 50 and in grooved strips 82 secured to the underside of the ceiling member 56. A pair of front members 84 are adapted to slide in the grooved strips 52 on the floor member 48 and engage

in the grooves of the strips 36. A pair of porch enclosing members 86 having ornamental openings 87 are adapted to slide in the grooved strips 54 and in grooved strips 88 secured at the front of the ceiling member 56. The side wall members 28 are provided with lower and upper window frames 90 and 92 which are similar to the window frames 20 carried by the rear wall member 12. These 10 window frames are adapted to be attached to openings in the sheet material of which the wall members are composed and as will be understood by reference to Fig. 3 each window frame member consists of two vertical 15 side strips 94, a lower strip 96 and an upper strip 98, these strips having grooves to receive the edges of the openings in the wall members. The inner edges of these strips are provided with shallow grooves for holding 20 pieces of transparent material 100, such as mica, celluloid or glass. Steps are attached to the front base member 42 in the following manner. A pair of supports 102 are provided 25 with angular locking lugs 104 adapted to be received in slots 106 in the member 42 whereby the supports may be secured in place by a sliding movement as will be understood by reference to Fig. 10. Grooved strips 108 aid in holding the supports 102 in place. A 30 number of steps 110 are placed on the successive horizontal portions of the supports 102 and, as will be understood from Figs. 4 and 10, are held in place by sliding into notches. The locking lugs 104 are slid into place before the floor member is positioned, and when the latter member is slid into its position, it holds the supports 102 from becoming detached. It will be understood that in assembling the parts of the house, the roof 35 portion is the last to be secured in place, and when the hooks 76 are engaged with the eyes 78, all of the parts will be securely held in place so that the house can be picked up and carried without liability of coming apart. 40 The roof member aids in holding the corners of the house together, and since the ceiling member is secured to the rear leaf of the roof it is prevented from sliding forwardly, the front members 84 keep the floor member 45 from sliding forwardly and the floor member retains the step supports in place.

I claim:

1. A collapsible toy house comprising a rear wall member, two side wall members, 55 means associated with said members for detachably holding them together at their corners, a ceiling member adapted to be slid in horizontal grooves carried by said side members, a roof member, and hooks for detachably securing said roof member and said ceiling member together, whereby both of them are held in place.

2. A collapsible toy house comprising a rear wall member, two side wall members, a 60 front base member, means associated with

said members for detachably holding them together at their corners, step supports having locking lugs for engagement with slots in said base member, steps adapted to be held upon said step supports by notches, a ceiling member adapted to be slid in horizontal grooves carried by said side members, a roof member and hooks for detachably securing said roof member and said ceiling member together whereby both of them are held in place. 70

3. A collapsible toy house comprising a rear wall member, two side wall members, a front base member, means associated with said members for holding them together at their corners, a floor member adapted to be slid into place between said side members, front members adapted to be slid in grooves carried by said floor member and to engage said side members for holding said floor member in place, a ceiling member adapted to be slid in horizontal grooves carried by said side member, a roof member, and hooks for detachably securing said roof member, and said ceiling member together whereby both of them are held in place. 75

4. A collapsible toy house comprising a rear wall member, two side wall members, a front base member, means associated with said members for detachably holding them together at their corners, step supports having locking lugs for engagement with slots in said base member, steps adapted to be held upon said step supports by notches, a floor member adapted to be slid into place between said side members and to hold said step supports in locked condition, a ceiling member adapted to be slid in horizontal grooves carried by said side members, a roof member hinged at its middle, and hooks for detachably securing the rear portion of said roof member and said ceiling member together whereby both of them are held in place. 90

5. A collapsible toy house comprising a rear wall member, two side wall members and a front base member, means associated with

said members for detachably holding them together at their corners, a floor member adapted to be slid into place between said side members, a ceiling member adapted to be slid into place between said side members, partition members adapted to slide in grooves carried by said floor member and by said ceiling member, front members adapted to slide in grooves carried by said floor member and to engage said side members for holding said floor member in place, porch enclosing members adapted to slide in grooves carried by said floor member and by said ceiling member, a roof member which assists in holding the corners together and means for detachably securing said ceiling member and roof member together. 110

In testimony whereof I hereunto affix my signature.

GUNIL J. HANSON.
